UNITED STATES PATENT OFFICE.

WILLIAM S. WEEDON, OF WOODBURY, NEW JERSEY, ASSIGNOR TO GENERAL ELECTRIC COMPANY, A CORPORATION OF NEW YORK.

ELECTRIC-ARC LAMP.

No. 889,163.

Specification of Letters Patent.

Patented May 26, 1908.

Original application filed May 20, 1904, Serial No. 208,923. Divided and application filed September 21, 1904. Serial No. 225,296. Renewed October 22, 1906. Serial No. 340,041.

To all whom it may concern:

Be it known that I, WILLIAM S. WEEDON, a citizen of the United States, residing at Woodbury, county of Gloucester, State of New Jersey, have invented certain new and useful Improvements in Arc-Lamps, of which the following is a specification.

My present invention relates to arc lamps, more particularly to that type in which the electrodes employed insure a flaming or luminous arc, though all of the features of my invention are not limited to use with such electrodes.

The object of my present invention is an arrangement whereby a suitable draft through the lamp can be obtained.

The various features of novelty which characterize my invention are pointed out with particularity in the claims annexed to and forming a part of this specification. For a better understanding of my invention, however, reference may be made to the accompanying description and drawings in which I have illustrated and described one embodiment of my invention.

Of the drawings, Figure 1 is an elevation of an arc lamp equipped with my invention with parts broken away and in section, and Fig. 2 is a perspective view showing a portion of the air screen.

Referring to the drawings, 1 represents the upper cap or top member of the lamp proper. A disk-shaped platform 2 is connected to the cap 1 by a tubular member 3. A tubular member 4 in line with the tubular member 3 extends a short distance above the cap 1. Lateral openings 5 in the wall of the member 4 at its upper end are shielded by a hood 6 carried at the upper end of the member 4. Suitable provisions, not shown in the drawings, may be provided for engaging the hood member 6 to support the lamp. The members 3 and 4 may be integral with each other but are preferably separable and may be secured to the cap member 1 by a threaded connection. Similarly the platform 2 may be supported from the lower end of the member 3 by a threaded connection.

A tubular member 7 in line and in open communication with the members 3 and 4 is secured to but insulated from the under side of the platform 2. Bowed members 8 pivotally secured to opposite sides of the tubular member 7 have clamped between their

ends the ends of an arc-shaped bar 9 which forms the positive electrode of the lamp. The bar 9 is formed of some material such as wrought copper which is a good conductor of heat and electricity and is not readily oxidized at the temperature to which it is subjected. Slots 10 are formed in opposite sides of the member 7 at its lower end to admit the passage through the member 7 of the bar 9. A projection 8' from one of the bowed members is connected by links or bars 11 to a U-shaped armature 12 which with its co-operating solenoid coils 13 is located between the cap 1 and the platform 2.

A tubular member 15 passing through an aperture formed for the purpose in the platform 2 has secured to its lower end an arm 16 which carries a socket 17 at its free end, in which the negative electrode 18 of the lamp is held in line with the axis of the tubular member 7. The electrode 18 is formed of or contains some material, such for instance as magnetite, titanium oxid or their mixtures, titanium carbide or the like, which in consuming gives a flaming or luminous arc.

I have not thought it necessary to illustrate and describe in detail the lamp mechanism located between the hood 1 and the platform 2, by means of which the movements of the electrodes 9 and 18, necessary to the proper operation of the lamp, are obtained as this mechanism forms no part of my present invention. Moreover, this mechanism and its operation are illustrated and described in detail in my application for patent on arc lamps, Serial No. 208,923, filed May 20, 1904, of which the present application is a division. Novel features disclosed in the present application, but not claimed therein, are claimed in the parent application referred to.

A casing 25 which may be formed of sheet metal or the like incloses the lamp mechanism located between the cap 1 and the platform 2, the upper end of the casing being secured to the cap 1 in any suitable manner as by means of screws 26. The lower end of the casing closely embraces the platform 2. Apertures 27 are formed in the lower end of the casing above the platform 2, through which air may enter the casing to ventilate the lamp mechanism. The heated air passes out of the casing at its upper end, suitable spaces being left between the casing and the hood

for that purpose. A hood or waterguard 28 surrounds the lower end of the casing to protect the apertures 27. An annular hood or member 29 secured to the casing below the hood 28 supports a suitable transparent or translucent globe 30 in any suitable manner as by screws 31. The globe 30 which surrounds the lamp mechanism located below the platform 2 is formed with a large opening at its lower end. A sheet metal annular member 32 is secured to the lower end of the globe in any suitable manner as by screws 33 which engage the globe above the out-turned end portion 34. A cylindrical member 35 having its lower end flared outward somewhat as shown, fits snugly in the central opening of the annular member with its axis in line with the axis of member 7. The member 35 may be secured to the annular member 32 by soldering or it may be detachably connected to the member 32. A wire netting 36 of comparatively fine mesh is secured to and extends across the upper end of the cylindrical member 35. A somewhat similar netting 37 extends transversely across the cylindrical member 35 about midway between its ends. This netting may be supported by annular members 38 and 39 as shown. It will be observed that the lower netting 37 is about in a plane with the lower end of the annular member 32, while the upper netting 36 is considerably above this plane. As a result of this construction, when the lamp is located out of doors or elsewhere where it is subject to more or less violent gusts of wind, the provisions of the cylindrical member 35 and the two screens or nettings separated by some distance, as shown, prevent any sudden inrush of air into the interior of the globe. This is an important advantage, as with lamps of this character it is desirable for their proper operation to admit a sufficient amount of air in the casing to insure that the natural draft created by the heat of the arc will carry the arc products up through the tubular members 7, 3 and 4 to the apertures 5 through which they are discharged into the outside air. This draft tends materially to steady the arc which extends between the electrodes. A variation in the amount of the draft, particularly a sudden variation, produces a disturbing influence upon the operation of the lamp. By the use of the construction shown disturbances produced by gusts of the outside air are reduced to a minimum. It may be desirable to admit a small amount of air at the junction between the annular member and the lower end of the globe and at the junction between the upper end of the globe and the hood. In many cases, however, it may be desirable to make

these joints substantially air-tight, all of the air necessary to produce proper draft being then admitted through the cylindrical member 35.

In some cases I may dispense with the use of more than one screen, and I may also dispense in some cases with the use of the cylindrical member 35 or may modify its form, as, while the particular construction described works very well in practice, I do not consider that my invention is limited to the particular arrangement of parts shown.

What I claim as new and desire to secure by Letters Patent of the United States, is,—

1. In an arc lamp, a draft tube, a pair of electrodes so arranged that the arc between them is in line with the axis of the draft tube and immediately below its lower end, a globe inclosing the arc having an opening formed in it in line with and below the draft tube, a cylindrical member in line with the draft tube, and one or more air screens extending transversely to said member.

2. In an arc lamp, a draft tube, a pair of electrodes arranged to produce an arc extending in line with said draft tube, a globe surrounding said arc, an aperture in said globe in line with said arc and said tube, and a screen located in said aperture which allows the passage of air sufficient for the operation of the lamp but which prevents sudden gusts of air from entering said globe.

3. In an arc lamp, an inclosing globe surrounding the arc, a passage leading therefrom through which the arc products are carried by natural draft, an aperture in the globe through which the air necessary for the proper operation of the lamp may pass, and a comparatively fine wire screen extending across such aperture to prevent disturbing air currents from being sent up within the globe by gusts of the air surrounding the globe.

4. In an arc lamp, a draft tube, means for establishing an electric arc adjacent one end of said tube, a globe surrounding said tube, an aperture in said globe substantially in line with said draft tube, and means for preventing sudden fluctuations in the amount of air passing through said aperture.

5. In an arc lamp, a draft tube, a pair of electrodes so arranged that the arc between them is in line with the draft tube, a globe surrounding the said arc, an aperture in the globe below the said arc and in line with said draft tube, an upwardly-extending cylinder surrounding said opening, and a screen closing said cylinder at a point above said opening.

6. In an arc lamp, a draft tube, a pair of electrodes arranged to produce an arc in line with the draft tube, a globe surrounding a portion of said tube and said arc and having an opening formed in it in line with said tube,

a cylinder surrounded by said opening and projecting inward toward said tube, and a screen for closing said cylinder.

7. In an arc lamp, electrodes, a globe surrounding said electrodes and having an opening beneath the electrodes, a cylinder surrounded by said opening and projecting toward said electrodes, and a screen closing said cylinder at a point above said opening.

10 8. In an arc lamp, a cap for closing the end of a globe having a central opening and a cylinder surrounding said opening and projecting laterally from the cap, and one or more screens extending across said cylinder.

15 9. In an arc lamp, an open-ended globe and a cap for closing said globe, said cap having a central opening and a cylinder which is

surrounded by said opening and projects into the interior of the globe, and a screen which closes said cylinder.

20

10. In an arc lamp, a draft tube, a globe surrounding the lower end of the draft tube, an open-ended cylinder arranged in line with the draft tube and having one end projecting into the globe and the other end projecting outside of the globe, and a pair of electrodes arranged so as to form an arc between and in line with said draft tube and said cylinder.

In witness whereof, I have hereunto set my hand this tenth day of September, 1904. 30

WILLIAM S. WEEDON.
